UNITED STATES PATENT OFFICE.

HERBERT S. BLYNT, OF BRADDOCK, PENNSYLVANIA.

NON-REFILLABLE BOTTLE.

SPECIFICATION forming part of Letters Patent No. 624,161, dated May 2, 1899.

Application filed February 10, 1898. Serial No. 669,828. (No model.)

To all whom it may concern:

Be it known that I, HERBERT S. BLYNT, a citizen of the United States, residing at Braddock, in the county of Allegheny and State of Pennsylvania, have invented certain new and useful Improvements in Non-Refillable Bottles; and I do declare the following to be a full, clear, and exact description of the invention, such as will enable others skilled in the art to which it appertains to make and use the same, reference being had to the accompanying drawings, and to the letters of reference marked thereon, which form a part of this specification.

The object of my invention is to provide a simple, cheap, and efficient non-refillable bottle; and the invention consists of the several details of construction and combinations of parts hereinafter fully described, and particularly pointed out in the claim.

In the accompanying drawings, Figure 1 is a sectional view of a portion of a bottle embodying my invention. Fig. 2 is a perspective view of one of the valves employed in carrying out my invention; Fig. 3, a section of the same; Fig. 4, a perspective view of a check-valve; Fig. 5, an end view of the same; and Fig. 6, a sectional view of the bottle-neck, the valves being removed.

Similar reference-letters indicate similar parts in the several figures.

A indicates the body of the bottle, and b its neck. The upper end of the neck forms a cork-receiving chamber a, and at the bottom of this chamber the bore of the neck is reduced, thereby forming the shoulder a' and a valve-chamber a². At the bottom of the chamber a² the bore is still further reduced to form the conical valve-seat a³ and the valve-chamber a⁴, which communicates with the interior of the body of the bottle. Between the shoulder a' and the valve-seat a³ an annular groove a⁵ is formed in the wall of the valve-chamber a², and a bead b' is formed on the exterior of the neck opposite the groove.

B indicates a valve the stem of which is adapted to fit loosely in the chamber a² in such manner that liquid can flow between it and the wall of the chamber. The head b⁵ of this valve is adapted to seat on the shoulder a' and is of less diameter than the cork-chamber a. The stem of the valve B is provided

with oppositely-arranged grooves b⁶, which are connected at their upper ends by an opening extending transversely through the stem. 55 A piece of spring-wire is inserted through said transverse opening, and the end portions of the wire are bent downwardly at nearly a right angle to form the spring-arms b³, which lie partially in the grooves b⁶. The free ends 60 of these arms are bent outwardly, as indicated by b⁴, and the bent ends are adapted to be sprung into the annular groove a⁵ when the valve is in place in the neck of the bottle and will prevent the withdrawal of the valve. 65

C indicates a check-valve the head c of which is adapted to rest on the valve-seat a³ and prevent entrance of liquid through the neck to the body of the bottle. The stem c' of this valve will work freely in the valve-chamber a⁴ and permit the liquid to flow from the bottle between it and the wall of the chamber.

After the bottle is filled the valve C will be first put in place, next the valve B, and finally 75 the cork. To discharge the liquid, the cork must be withdrawn, and by tilting the bottle the pressure of the liquid will unseat the valves C and B and permit the liquid to escape, it being understood that the annular 80 groove a⁵ is of sufficient width to permit a limited movement of the bent ends b⁴ of the spring-arms longitudinally of the neck of the bottle. The upper end of the valve B will be of metal or glass to prevent the insertion 85 of an implement therein for the purpose of withdrawing it, and it is evident that as long as this valve is in the neck of the bottle the valve C cannot be held from its seat to permit the bottle to be filled. 90

Having described the invention, I claim—

The combination with a bottle the neck of which is provided with a cork-receiving chamber at its upper end, a valve-chamber of less diameter than the cork-receiving chamber immediately below the latter with a shoulder at their junction, and a second valve-chamber below the first valve-chamber of less diameter than the latter a conical valve-seat being formed at their junction and the first valve-chamber having an annular groove in its wall intermediate its upper and lower ends, of a check-valve the stem of which fits loosely in the second valve-chamber and the head of

which fits in the said conical valve-seat, a second valve the stem of which fits loosely in the first valve-chamber and the head of which is of less diameter than the cork-receiving chamber and adapted to rest on the said shoulder, the said stem having oppositely-disposed longitudinal grooves connected at their upper ends by a transverse opening, and a piece of spring-wire extending through said opening with its end portions bent to form spring-arms seated partially in said grooves, and the free

ends of said arms being bent outwardly to engage in said annular groove, the groove being wide enough to permit limited movement of the said bent ends therein longitudinally of 15 the bottle-neck, substantially as described.

In testimony whereof I affix my signature in presence of two witnesses.

HERBERT S. BLYNT.
